UNITED STATES PATENT OFFICE.

LOUIS B. NEWELL, OF BALTIMORE, MARYLAND.

DESIGN FOR A GLASS BOTTLE.

Application filed December 16, 1921. Serial No. 522,939. Term of patent 3½ years

To all whom it may concern:

Be it known that I, LOUIS B. NEWELL, a citizen of the United States, residing at Baltimore, in the county of Baltimore and State of Maryland, have invented a new, original, and ornamental Design for Glass Bottles, of which the following is a specification, reference being had to the accompanying drawing, forming part thereof.

Fig. 2 is a plan view thereof.

I claim:

The ornamental design for a glass bottle, as shown.

LOUIS B. NEWELL.
